UNITED STATES PATENT OFFICE.

ABRAM E. SELTZER, OF LEBANON, PENNSYLVANIA.

DESIGN FOR BACK FOR PAPER-CLIPS.

SPECIFICATION forming part of Design No. 16,386, dated November 17, 1885.

Application filed October 12, 1885. Serial No. 179,737. Term of patent 7 years.

To all whom it may concern:

Be it known that I, ABRAM E. SELTZER, a citizen of the United States, residing at Lebanon, in the county of Lebanon and State of Pennsylvania, have invented and produced a new and original Design for Backs for Paper-Clips; and I do hereby declare the following to be a full, clear, and exact description of the invention, such as will enable others skilled in the art to which it appertains to make and use the same.

Reference being had to the accompanying drawings, which form a part of this specification, Figure 1 represents a front elevation; Fig. 2, a side view.

The design has relation to backs for paper-clips in which a spring holds the paper in position; and it consists in the novel form and configuration thereof, as herein shown and described.

In the drawings which illustrate the design, the letter A indicates the base or bottom, which is rectangular (lozenge shaped) in form, as shown. B indicates a projecting finger extending out from one of the corners of the base, the upper end of which is slightly rounded at C, and the edges are beveled, as shown.

Having thus described my design, what I claim is—

The design for backs for paper-clips, consisting of a lozenge-shaped base, A, and a finger, B, projecting from one of the corners of the base, as shown and described.

In testimony whereof I affix my signature in presence of two witnesses.

ABRAM E. SELTZER.
